UNITED STATES PATENT OFFICE.

ARTHUR W. NELSON, OF WILLIAMSPORT, PENNSYLVANIA

WINDOW SASH.

Application filed November 17, 1927. Serial No. 233,902.

While the invention relates primarily to window sashes and will so be described, it is to be understood at the outset that it is also applicable to doors embodying a glass pane.

5 Prior to my invention, sashes have been produced provided with grooves in their inner edges to receive the edge portions of panes of glass, one side member or rail of the sash being detachable to permit insertion or removal of the pane, as occasion may demand. Then too, spring devices have been used within the grooves to yieldably hold the glass pane tightly against one side of said grooves. It is the object of my invention however to provide 15 a new and improved construction in which exceptionally simple and inexpensive, yet efficient, reliable, and easily applied and removed spring devices, are provided to hold the glass pane.

20 With the foregoing in view, the invention resides in the novel subject matter hereinafter described and claimed, description being accomplished by reference to the accompanying drawing.

25 Fig. 1 is a fragmentary side elevation of a sash improved in accordance with my invention.

Fig. 2 is a vertical section on line 2—2 of Fig. 1.

30 Fig. 3 is a horizontal section on line 3—3 of Fig. 1.

Fig. 4 is a side elevation of one of the springs.

In the drawing above briefly described, the 35 numeral 5 denotes a sash whose upper rail 6 is detachably secured in place by screws such as 7, the usual mortise and tenon joints being provided at the sash corners. At two corners, these joints are held assembled by the 40 usual pins 8, while screws such as 7 are used instead of such pins, at the other two corners.

The inner edges of the sash are formed with registering grooves 9, and the grooves may extend entirely to the horizontal and vertical edges of the sash, so that the open lower ends 10 of the two vertical grooves, serve to drain out any water which would otherwise collect in the lowermost groove. This water is of course received by the window sill and 45 runs off without producing any harmful results, in which connection it may be explained that the groove walls may be effectively painted before assembly of the sash.

A glass pane 11, has its edge portions received in the grooves 9, the thickness of said pane being less than the width of the grooves.

Short, one-piece strip-metal springs 12 are disposed under tension between the pane 11 and one side of each groove 9, thereby tightly holding the pane against the opposite side 60 of said groove. Each spring 12 is longitudinally bowed and has its crest 13 disposed in contact with the pane, while the ends of said spring are formed with sharpened edges 14 which bite into the side wall of the groove 65 and thus hold the spring against slippage. Preferably, the end portions of the spring 12 are tapered so that the length of the sharp edges 14 is decreased, permitting them to more readily penetrate the wood, under the 70 inherent resiliency of said spring, and permitting passage of water at said ends.

The pane 11 is inserted with the detachable rail 6 removed, and said rail is then secured in position. Then, the springs 12 which normally have a greater curvature than shown in Figs. 2 and 3, are partially straightened out and inserted into the grooves 9, as shown in said figures. When so positioned, they tightly hold the pane against the inner sides 80 of the grooves 9 and thus effectively take the place of putty, although they are in reality more efficient, as the pane is permitted to yield under wind pressure, without danger of loosening its securing means.

85 Whenever a pane is broken, it may be easily removed and another substituted, with the use of no tools other than a screw driver.

The sash shown, is a lower sash. When adapting the invention to an upper sash, its 90 lower rail is made detachable and the heads of the screws 7 are countersunk into the inner side of said rail.

On account of the excellent results obtainable from the details disclosed, they are 95 preferably followed. However, within the scope of the invention as claimed, minor variations may be made.

I claim:—

1. In a sash or analogous device having 100 registering grooves in the inner edges of its side members, and a pane whose edges are received in said grooves; a plurality of one-piece strip-metal springs disposed under tension between said pane and one side of each 105 groove, each of said springs being longitudinally bowed and having the crest of its bow in contact with the pane, the ends of each spring having sharp edges which bite into said side of the grooves to prevent slippage of 110 the springs.

2. In a sash or analogous device having

registering grooves in the inner edges of its side members, and a pane whose edges are received in said grooves; a plurality of one-piece strip-metal springs disposed under tension between said pane and one side of each groove, each of said springs being longitudinally bowed and having the crest of its bow in

contact with the pane, the ends of each spring being tapered and having sharp edges which bite into said side of the grooves to prevent ¹⁰ slippage of the springs.

In testimony whereof I have hereunto affixed my signature.

ARTHUR W. NELSON.
